UNITED STATES PATENT OFFICE.

ROY T. AXE, OF SYRACUSE, NEW YORK, ASSIGNOR TO THE O. M. EDWARDS COMPANY, INC., OF SYRACUSE, NEW YORK, A CORPORATION OF NEW YORK.

SCREEN FOR DOUBLE RAILWAY-CAR WINDOWS.

1,359,146.

Specification of Letters Patent. Patented Nov. 16, 1920.

Application filed October 31, 1917. Serial No. 199,446.

To all whom it may concern:

Be it known that I, Roy T. Axe, a citizen of the United States, and a resident of Syracuse, in the county of Onondaga and State 5 of New York, have invented a certain new and useful Screen for Double Railway-Car Windows, of which the following is a specification.

This invention relates to windows especially railway car windows, and has for its object a particularly simple and efficient screen construction, and means of applying it between the double sashes of railway cars; and the invention consists in the novel features and in the combinations and constructions hereinafter set forth and claimed.

In describing this invention, reference is had to the accompanying drawing in which like characters designate corresponding parts 20 in all the views.

Figure 1 is a front elevation, partly in section, of a window frame, with my screen therein, the sashes being removed.

Fig. 2 is a vertical sectional view taken on 25 the plane of line 2—2, Fig. 1.

Fig. 3 is an enlarged sectional view taken on the plane of line 3—3, Fig. 1.

Fig. 4 is an elevation of the screen.

Fig. 5 is a detail view of the strip inserted 30 in the rails and stiles of the screens to hold the screening in position.

Fig. 6 is a fragmentary detail sectional view of the screen, the parts being shown as displaced slightly outwardly.

This invention comprises generally, a 35 frame, a double sash as inner and outer sashes movable in the frame and having their opposing faces spaced apart, and a screen movable vertically in the frame between the sashes and independently of the sashes along the parting strips.

1 designates the window frame which may be of any suitable form, size and construction, it being here shown as formed of sheet 45 metal and as provided with the usual outer stops 2, parting strips 3 and inner stops 4 which confine guideways for the outer and inner sashes 5, 6. The sashes 5, 6 may be of any suitable form, size and construction 50 and are here shown as balanced, partly balanced or overbalanced by spring rollers 7 and 8 which are connected thereto by cables or chains 9, the spring rollers tending to raise the sashes, as will be understood by 55 those skilled in the art. The window sashes

are provided with sash holding devices having handles 10 flush with the front faces of the sashes and operating rock shafts 11 on which are mounted the usual detents coacting with racks 12 formed on the parting 60 strips 3 and the stops 4.

13 is the screen movable along guides 14 detachably secured to the parting strips 3. The screen is here shown as provided with a sheet metal sash or frame including stiles 65 and rails formed from sheet metal and having channels 15 opening through one face thereof, a screening 16 having its margin 17 extended into the channels 15 and strips 18 inserted in the channels 15 onto the margins 70 17 of the screening to secure the screening to the frame. The stiles and rails of the sash are also formed with channels 19 in their edge faces, the channels 19 in the stiles coacting with and receiving the guides 14, 75 and the channels 19 along the rails, particularly the lower rail of the frame having a weather stripping device therein. Said device includes a tube, as a rubber tube 20, which is held in position by a strip 21 extended through the tube and pressed into the channel 19 to clamp the interposed portion of the tube in said channel 19. The strip 21 is in the form of a U-shaped channel as shown in Fig. 6. 80

The screen is held in its closed position and at different elevations by means of locking bolts 22 extending edgewise through the stiles of the screen frame and operable by handles 23 located between the planes of the 90 front and rear faces of the screen. These handles 23 are located or exposed at the inner edges of the stile of the screen frame in front of the screening and each consists of resilient metal strips extending lengthwise 95 of the stile and fixed at one end to the stile and having its other end looped to form a handle. The bolts 22 coöperate with suitable openings 25 in the guides 14 when the screen is in its closed position, and with indentations 26 formed in said guides 14 when the screen is elevated.

The screen is held from rattling by spring pressed devices carried by one of the walls of the channel 19 in each of the stiles and 100 pressing against the opposing face of the guide 14, and as here shown, these devices consist of pins or shoes 27 extending through one of the walls of said channel 19 and acted upon by the intermediate part of a bow 110

spring 28 having its ends secured at 29 to the stile of the screen frame.

Each rail and stile of the sash frame is formed separately of two strips of metal 5 30, 31, the strip 30 being formed to have flanges 32, 33 extending in opposite directions from a connecting web 34 and constituting the front and rear sides of the body of the sash. The web 34 forms one side of 10 the channel 15. The strip 31 is similarly bent to have flanges 35, 36 and webs 37. The flange 36 lies flat on flange 33 with its free edge abutting against the web 34 at the angle of the web 34 and the flange 33, the 15 flange 35 is opposed to the margin of the flange 33 and together with the web 37 and said margin forms the channel 19. The web 37 is opposed to the web 34 and together therewith and the flange 36 forms the channel 15. The strips 30, 31 are welded together and are mitered at their abutting ends where they are welded together. The screening adjacent its margin turned in the channel 15, passes over the flange 32. The 20 strips 18 which hold the screening in the channels are separate from each other and hence are separately receivable. Said strips 25 18 are also mitered at their abutting ends.

The guides 14 are bent in the form of a 30 U-shaped channel with flanges 38 abutting against the opposing edge faces of the parting strips 3. One of said guides includes a lower section which is separable from the upper section at 39, that is, at a point 35 slightly above the upper edge of the screen when the screen is in its closed position or slightly below the lower edge when the screen is in its raised position and the guides are detachably secured to the parting strips 40 by screws 40.

When it is desired to remove the screen, the front stops 4 are removed to permit the sash to be swung outwardly. The screws 40 of the lower section of the guide for the 45 screen are then removed so that said lower section can be removed to permit the screen to be pulled out. The screen is first raised to permit the lower section of the guide to be removed and then lowered into a position to be removed.

Owing to the construction of the screen and the arrangement of its handles it can be made thin enough to be placed between the usual inner and outer sashes of railway cars and further, owing to the arrangement of the guides 14, the screen can be readily applied to existing double windows of railway cars.

What I claim is:

60 1. In a window construction, the combination of a frame, inner and outer sashes movable in the frame and having their opposing faces spaced apart, parting strips between the sashes and formed with guides 65 one comprising a removable section located

below the screen when in its raised position, and a screen movable between the sashes and along the guides, substantially as and for the purpose set forth.

2. In a window construction, the combination of a frame, inner and outer sashes movable vertically in the frame and having their opposing faces spaced apart, guides associated with the frame in the space between the sashes, a screen having its frame 70 slidably interlocked with the guide, one of the guides including a removable section, and means for detachably securing said section in position, substantially as and for the purpose specified.

3. A window construction comprising a sash frame, including stiles and rails formed with a channel opening through one face thereof and with a channel opening through the edge faces, screening having its margin 80 extending into the first mentioned channel, strips inserted into the first-mentioned channel onto the margin of the screening, and weather strips in the channels at the edges of the rails, in combination with a 90 window having guides extending into the channels at the edges of the stiles, substantially as and for the purpose specified.

4. In a window construction, the combination of a frame, inner and outer sashes 95 movable in the frame and having their opposing faces spaced apart, the frame being provided with guides in the space between the sashes, a screen movable along the guides between the sashes, and a lock for holding 100 the screen at different elevations, the lock having handles exposed on the inner edges of the stiles thereof between the front and rear planes of the faces of the screen, substantially as and for the purpose described.

5. In a window construction, the combination of a frame formed with a guide, a sash formed with a channel in the edge face of one of its stiles, for receiving the guide and friction means for holding the sash from 110 rattling including a part extending through a wall of the channel in position to press against the guide, and a spring carried by the sash and pressing on said part, substantially as and for the purpose specified.

6. In a window construction the combination of a frame formed with a guide, a sash formed with a channel in the edge face of one of its stiles for receiving the guide and friction means for holding the sash from rattling including a part extending through a wall of the channel in position to press against the guide, and a spring carried by the sash and pressing on said part, said spring lying on the outer face of 120 said wall of the channel, substantially as and for the purpose set forth.

7. In a window construction the combination of a frame formed with a guide, a sash formed with a channel in the edge face 125

of one of its stiles for receiving the guide, and friction means for holding the sash from rattling including a part extending through a wall of the channel in position to 5 press against the guide, and a spring carried by the sash and pressing on said part, said spring lying on the outer face of said wall of the channel, and being secured at its ends to said wall and having its interme-

diate portion tensioned and acting on said 10 part, substantially as and for the purpose described.

In testimony whereof, I have hereunto signed my name, at Syracuse, in the county of Onondaga, and State of New York, this 15 15th day of October, 1917.

ROY T. AXE.
